UNITED STATES PATENT OFFICE

2,556,629

PILLOW FOR PRONE POSTURE SLEEPING

Catherine M. O'Brien, Santa Monica, Calif.

Application October 4, 1948, Serial No. 52,716

3 Claims. (Cl. 5—337)

1

The present invention relates to a novel and improved pillow construction characterized by complementary pillows coordinated in predetermined and spaced relation and the object of the invention is to thus provide what I call a prone posture pillow, the same serving to promote comfort, relaxation and to insure refreshing and recuperating sleep while the user occupies a prone position, lying primarily on and supported by the weight of the abdomen.

Briefly, in carrying out a preferred embodiment of the invention, I have evolved and produced a two-in-one pillow construction characterized by a pair of complementary cushions of non-allergic soft moltex or equivalent materials, these being separately mounted in individual frames which are, in turn, separably and adjustably supported on a single base, allowing adjacent longitudinal edge portions of the cushions to be spaced apart, generally in divergent relationship, and providing a split pillow which is conducive to the circulation of air and which provides an effective pocket for the face and nose.

Another object of the invention is to provide a special pillow construction of the kind referred to, the usual curvate or convex surfaces of the pillow-cushions being such as to provide, between themselves, a suitable space for effective reception of the face of the user, thus promoting comfort and allowing the sleeper to keep the head and neck in alignment with the spine and conformable to the contours of the spinal curves, the non-allergic materials used, in the cushions, being of effectiveness and appreciable advantage to asthmatic and hay fever sufferers.

More explicitly, in carrying out a preferred embodiment of the invention, I provide a wooden or equivalent base frame and support duplicate auxiliary frames thereon in superimposed relation, the auxiliary frames being such that they serve to permit the pillow-cushions to be selectively placed and held in spaced positions.

Other objects and advantages will become more readily apparent from the following description and the accompanying illustrative drawings.

In the drawings:

Figure 1 is a fragmentary perspective view showing a portion of a bed, mattress or the like and illustrating a two-way or two-in-one pillow constructed in accordance with my ideas.

Figure 2 is a section on the line 2—2 of Figure 1, looking in the direction of the arrows.

Figure 3 is a top plan view, pillows or cushions removed, showing the main and auxiliary frames

and their adjustable association and relationship in full and dotted lines, respectively.

Figure 4 is a fragmentary perspective view of portions of the main or base frame and one of the auxiliary frames.

Figure 5 is a fragmentary perspective view of a corner portion of the main base frame.

Referring now to the drawings and particularly to Figure 1, the numeral 7 denotes a bed, couch, 10 mattress or other surface upon which the user may recline in a prone or other similar restful position. The pillow, instead of being of one piece construction, is of a duplex or two-in-one type. It is therefore referred to as a "pillow construction." The individual pillows or cushions, which may be called pillow-cushions, are denoted by the numerals 8 and 9 and are duplicates of one another and are of elongated semi-cylindrical or equivalent cross-sectional form 15 and are preferably of non-allergic soft moltex or an equivalent material.

The invention is intended to be constructed in three sizes, large, medium and small and the frame members or units are constructed of wood, 20 metal or plastic. The main or base frame is of general rectangular form and is denoted by the numeral 10 and includes longitudinal side members 11 and transverse cross or end members 12 and 13 respectively. The cross member 12 is provided at central spaced points with upstanding dowels or assembling and pivoting studs 14 and 15 (see Figs. 3 and 5). At the top the cross or frame member 13 is provided with two sets of three adjusting or keeper sockets 16, 17 and 18 arranged in suitable arcuate paths and adapted 25 to accommodate the keeper studs or dowels 19 fixedly carried by the coacting auxiliary pillow holding frames 20 and 21, respectively. Said frames 20 and 21, at the ends where they match 30 with the pins 14 and 15 are provided with apertures or holes 22 and 23 (not detailed, see Figure 3) permitting the two frames 20 and 21 to be swingably and hinged mounted atop the underlying or base frame. Thus, and all together there are three frames, a main or base frame supporting a pair of duplicate auxiliary frames, the latter serving as pillow holders for the pillow-cushions 8 and 9. The pillow-cushions are stuffed partly down into the auxiliary 35 frames or holders 20 and 21 as shown in Figure 2, thus permitting said pillows to reside effectively in the frames and against normal displacement. The adjacent inner longitudinal and opposed edge portions of the respective pillows are 40 spaced apart in parallelism when the auxiliary

2

frames are lined up with the main frame. The space however may be changed to somewhat V-shaped form by separating the pillows and pillow holding frames. The adjustment is maintained by anchoring the pins 19 in the selectively usable sockets 16, 17 and 18 as is obvious.

Changes in shape, size, materials and rearrangement of details and parts may be resorted to in actual practice, so long as they do not depart from the spirit of the invention or the scope of the appended claims, as is well understood.

Having described the invention, what is claimed as new is:

1. A pillow construction for face-down prone posture sleeping comprising a portable rigid base adapted to be placed in a predetermined position on a bed mattress or the like, a pair of individual holders superimposed on and hingedly attached to said base, said holders being in the same horizontal plane with each other, having adjacent marginal edge portions normally in spaced parallelism but swingable in directions away from each other to occupy divergent positions, and a pair of duplicate complementary pillow-cushions corresponding in size and outline to and removably fitted on said holders.

2. A pillow construction for face-down prone posture sleeping comprising a portable rigid base adapted to be placed in a predetermined position on a bed mattress or the like, said base being a substantially rectangular frame embodying longitudinal frame members connected at corresponding ends by transverse frame members, one frame member being provided intermediate its ends with a pair of adjacent upstanding pivoting studs, a pair of substantially rectangular auxiliary frames superimposed on and normally confined within the marginal limits of said base frame, said auxiliary frames having adjacent edge portions in normally spaced parallelism, corresponding inward corner portions of said auxiliary frames being hingedly attached to said pivoting studs, the remaining longitudinal member of said base frame being provided with sets of selectively usable keeper sockets, the ends of said auxiliary

frames adjacent said sockets having keeper pins selectively engageable in said sockets.

3. A pillow construction for face-down prone posture sleeping comprising a portable rigid base adapted to be placed in a predetermined position on a bed mattress or the like, said base being a substantially rectangular frame embodying longitudinal frame members connected at corresponding ends by transverse frame members, one frame member being provided intermediate its ends with a pair of adjacent upstanding pivoting studs, a pair of substantially rectangular auxiliary frames superimposed on and normally confined within the marginal limits of said base frame, said auxiliary frames having adjacent edge portions in normally spaced parallelism, corresponding inward corner portions of said auxiliary frames being hingedly attached to said pivoting studs, the remaining longitudinal member of said base frame being provided with sets of selectively usable keeper sockets, the ends of said auxiliary frames adjacent said sockets having keeper pins selectively engageable in said sockets, and a pair of substantially duplicate readily attachable and removable pillow cushions, said pillow cushions corresponding in general shape and size to said auxiliary frames and being removably lodged in position on said auxiliary frames for use and adjustment in conjunction with the latter.
